UNITED STATES PATENT OFFICE.

HEINRICH HENRICH, OF NEW YORK, N. Y., ASSIGNOR TO HIMSELF AND
HENRY HENZE, OF SAME PLACE.

IMPROVEMENT IN DIES FOR FORMING BASILS OF LOCKETS.

Specification forming part of Letters Patent No. 133,986, dated December 17, 1872.

To all whom it may concern:

Be it known that I, HEINRICH HENRICH, of the city, county, and State of New York, have invented a new and useful Improvement in Die for Forming Locket, Stud, and Button Basils, of which the following is a specification:

Figure 1 is a side view of the movable die and a section of the stationary die for cutting out the blank, the plate being shown in place. Fig. 2 represents the blank cut out. Fig. 3 is a side view of the movable die and a section of the stationary die for bringing the blank into cup shape. Figs. 4 and 5 are sections, and a top or plan view, of the blank brought into cup shape. Fig. 6 is a top view of the lower or stationary die for cutting out the bottom of the cup-shaped blank and for forming the basil. Fig. 7 is a side view of the movable die and a section of the stationary die for cutting out the bottom of the cup-shaped blank. Fig. 8 is a sectional view of the cup-shaped blank with its bottom cut out. Fig. 9 is a section of the movable and stationary dies for forming the basil. Figs. 10 and 11 are a top and a sectional view of the formed basil.

Similar letters of reference indicate corresponding parts.

My invention has for its object to furnish an improved die for forming locket, stud, and button basils with inwardly-inclined sides and inwardly-projecting base-flange, and which shall be simple in construction, convenient in use, and effective in operation, enabling the basil to be formed quickly and accurately and in one piece; and it consists in a die, in the face of which is formed a groove having its inner side vertical and its outer side inclined, as hereinafter more fully described.

A represents the plate of gold or other metal out of which the basil is to be formed. B is the lower or stationary die having a hole formed through it, over which the plate A is placed to be cut by the descent of the movable die C. The blank D, thus cut out, is placed in the stationary die E, which is formed with a rounded shoulder around the hole formed through it. As the movable die F descends

it forces the flat blank D through the hole in the die E, producing a cup-shaped blank, G, with rounded angle or corner, as shown in Figs. 4 and 5. H is a stationary die having a recess or shoulder, h^1 , formed around the hole through it to receive the cup-shaped blank G to hold it while the bottom is cut out by the descent of the die I, bringing the blank into the form of a short tube having an inwardly-projecting flange around its lower end. J is the die by which the basil is formed. The face of the die J is made of such a size as to fit into the shoulder h^2 formed around and concentric with the shoulder h^1 . In the face of the die J is formed a groove, K, the inner side of which is vertical and the outer side inclined. The groove K is concentric with the face of the die J and with the shoulders h^1 h^2 of the die H. The groove K is so arranged that the lower edge of its outer or inclined side may coincide with the edge of the shoulder h^1 . The lower edge of the inner or vertical side should be a little inside of the edge of the hole through the die H.

The blank L, formed by the die I is placed in the shoulder h^1 of the die H. As the die J descends the lower part of the inclined side of the groove K strikes upon the upper edge of the blank L and forces it inward until the outer part of the die J strikes the shoulder h^2 . This operation completes the formation of the basil M, and leaves it in the form shown in Figs. 10 and 11.

The dies, blanks, and basil are shown in the drawing as being oval in form, but they may be made round with the same facility, and may be of any desired size.

Having thus described my invention, I claim as new, and desire to secure by Letters Patent—

A die, J, in the face of which, and concentric therewith, is formed a groove, K, having its inner side vertical and its outer side inclined, substantially as herein shown and described, and for the purpose set forth.

HEINRICH HENRICH.
